UNITED STATES PATENT OFFICE.

FRANK E. KITSMAN, OF SEATTLE, WASHINGTON.

CLIP FOR CONCRETE FORMS.

Application filed July 17, 1926. Serial No. 123,089.

My invention relates to improvements in clips that are adapted for holding together the lap boards used for making concrete forms. The principal objects of the invention are to provide a clip comprising a pointed end that may be driven into the two by four studs and a bracket end that is inserted between the lap joints of the ship-lap boards whereby the use of nails and the consequent splitting of the boards at their joints is eliminated. Other objects are to provide a clip of very simple construction that is reliable and efficient in use and which may be manufactured at comparatively small cost.

With the above and other objects in view which will appear as the description proceeds, the invention consists of the novel construction, adaptation, combination and arrangement of parts hereinafter described and claimed. These objects are accomplished by the device illustrated in the accompanying drawings, wherein:

Figure 1 is a view in perspective of a clip embodying the features of the invention;

Fig. 2 is a view in side elevation of the clip installed in a fragmentary portion of a concrete form;

Fig. 3 is a view in horizontal section taken substantially on a broken line 3, 3 of Fig. 2; and

Fig. 4 is a view in perspective showing a plurality of clips installed in a portion of a concrete form.

Referring to the drawings throughout which like reference numerals designate like parts, the numeral 5 indicates the body portion of the device which is flattened, as at 6, at one of its end portions.

A bracket is formed by bending the flattened portion downwardly at right angles thereto, as at 7, then horizontally and in parallel with the body portion 5, as at 8, then vertically and in parallel with the portion 7, as at 9. The end 10 may be slightly sharpened or tapered if so desired.

The other end of the body portion 5 is bent at 11 to form a short portion 12 at right angles thereto and is then bent round up on itself to form a curved head 13 from whence it projects outwardly at an angle slightly more than ninety degrees with the body portion to form a shank portion 14 with a sharpened end 15.

In the foregoing description it will be understood that the body 5, portion 12 and shank 14 are all in the same plane that is

normally horizontal, while the portions 7, 8 and 9 of the bracket end are all disposed in a plane at right angles to the foregoing plane and which is normally vertical.

Referring to Figs. 2, 3 and 4 the numeral 16 designates the two by four studs and the numeral 17 indicates the ship-lap or other boards used in making concrete forms. In the application of the device two of the boards are fitted together against the two by four with the bracket portion of the clip inserted between the lap joint thereof as clearly shown in Fig. 2. The point 15 is then driven home by hammering upon the head 13 until the body portion 5 bears against the two by four.

Due to the fact that the shank portion 14 is disposed at an angle greater than ninety degrees with the body portion 5, said shank and point 15 will sink into the stud 16 in a slantwise direction with the lap boards 17. This will result in drawing the lap board joint, that is embraced by the bracket portion of the device, snugly and securely against the stud as will be readily understood.

When the concrete has set the forms may be readily removed by pulling the shank portions 14 out of the studs with a pair of pliers or other instrument applied to the head 13.

It will now be obvious that I have provided a clip that will hold the lap boards securely against the studs. The use of nails which result in splitting the lap joints of the boards is entirely eliminated, and the boards may be used many times over without impairment by employing my clip.

Having thus described my invention, it being understood that minor changes may be resorted to without departing from its scope and spirit, what I claim and desire to secure by Letters Patent is:—

1. A clip comprising a main body, a pointed shank on one end of said main body arranged at substantially right angles thereto, and a substantially U-shaped bracket formed on the other end of said main body, said bracket embodying two spaced parallel sides disposed at substantially right angles to said main body and connected with each other by an end portion one of said sides being connected with the end of said main body.

2. A clip for securing ship lap timber to studding, comprising a main clip body, an integral pointed shank arranged at substantially right angles to said main clip body and adapted to be driven into the studding,

the other end of said main clip body being flattened and bent to form a substantially U-shaped bracket adapted to fit over the outermost tongue of two adjacent overlapping ship lap boards, the outer leg of said U-shaped bracket engaging the outside of said outermost tongue and the inner leg of said

U-shaped bracket hooking over and engaging the innermost tongue of said two overlapping ship lap boards.

In witness whereof, I hereunto subscribe my name this 12th day of July, A. D. 1926.

FRANK E. KITSMAN.
